UNITED STATES PATENT OFFICE

115,975

DESIGN FOR A SCARF

Sylvia Haggander Bammon, New York, N. Y., assignor to Girl Scouts (Incorporated), New York, N. Y., a corporation of the District of Columbia

Application April 14, 1939, Serial No. 84,283

Term of patent 3½ years

To all whom it may concern:

Be it known that I, Sylvia Haggander Bammon, a citizen of the United States of America, residing in the Borough of Bronx, city and State of New York, have invented a new, original, and ornamental Design for a Scarf, of which the following is a specification, reference being had to the accompanying drawing, forming a part thereof.

The figure is a plan view of a scarf, showing my new design.

I claim:

The ornamental design for a scarf, as shown.

SYLVIA HAGGANDER BAMMON.
